UNITED STATES PATENT OFFICE.

GEORGE ERNEST MALLOTT, CHRISTOPHER JOHNSON, AND JOHN WILLIAM MOORBY,
OF PRESTON, ENGLAND.

LOOM-REED-LOCKING MOTION.

1,114,999.

Specification of Letters Patent.

Patented Oct. 27, 1914.

Application filed January 20, 1914. Serial No. 813,303.

To all whom it may concern:

Be it known that we, GEORGE ERNEST MALLOTT, CHRISTOPHER JOHNSON, and JOHN WILLIAM MOORBY, subjects of the King of Great Britain, residing, respectively, at "Moorside," Ribbleton avenue, Preston, 5 Manchester road, Preston, and 10 Elijah street, Preston, all in Lancashire, England, have invented new and useful Improvements 10 in Loom-Reed-Locking Motions, of which the following is a specification.

The improvements relate to reed motions in looms for weaving, the object of which is to provide means whereby the reed may be 15 practically "fast" during normal operations, but become automatically "loose" or released when the shuttle fails to enter the shuttle box, in the manner hereinafter to be described.

It is well known that if, from any cause a 20 loom shuttle is checked in its motion from end to end of the slay, and remains in the shed at the time of beat-up, damage accrues to the warp by obstruction on the part of 25 such shuttle, and to prevent or minimize this the reed is either mounted so as to be capable of swinging out or yielding to the abnormal pressure, or means are provided to check the advance of the slay so that the full 30 beat-up may not take place. The latter device entails considerable shock to the loom, while the use of a permanently loose reed 35 limits the character of the fabrics produced in the loom. To overcome this difficulty,

means have been proposed to keep the reed 40 normally locked in position except at those times when the shuttle fails to enter the box and is trapped in the shed, when the reed is released by mechanical means and becomes 45 for the time being a loose reed. By our invention a reed of this character is provided with a retaining clamp and clamp connections which latter are of the kind which are movable transversely of the lower part of 50 the loom slay, for release of the reed, and are combined with means whereby each clamp connection is constantly locked in position whenever the loom is working properly, for retaining the reed whether the 55 shuttle is in the shuttle box or not, and is unlocked for release of the reed when the shuttle stops in the shed.

With reference to the accompanying drawings, Figure 1 is a cross sectional view, 55 partly in elevation, of the slay and reed por-

tion of a loom provided with means for holding fast or releasing the said reed under the conditions aforesaid, and according to one form of our invention. Fig. 2 is a similar view to Fig. 1, the parts being, however, in the "released" position. Fig. 3 is a sectional plan view of Fig. 1, a few details being omitted. Fig. 4 is a front view, slightly in section, of a portion of the loom slay, provided with means according to the 65 previous figures. Fig. 5 is a modification of a part of the mechanism, and illustrated on a smaller scale to the rest of the figures. Fig. 6 is an end view of the shuttle box and slay sword, (a portion of the slay being 70 shown in section), fitted with our improved mechanism; and Fig. 7 is a plan view of a detail shown in Fig. 6.

In Figs. 1, 3, and 4, the reed and parts relating to the same are shown in the locked 75 position, which is maintained while the shuttle is operating properly; in Fig. 6 the position indicated is when the shuttle is not in the box, in Fig. 2, as above stated, when the reed is released.

a is the slay, from the top bar *a*¹ of which is suspended the reed *b*, as is well understood.

The reed is normally held fast by the bar *c* (omitted from Fig. 3), which bar is attached to a number of supports, such as *c*¹, in connection with the special slidable parts, such as *d*, the whole forming a clamp device according to our invention.

The parts *d* are arranged at suitable intervals along the length of the slay, and each one of which is, in the present example, assumed to consist of a hollow frame forming side supports, connected together at the one end by the part *c*¹, and at the other end spanned by a movable block *d*¹. The said part *d* is shown mounted in a support or bracket piece attached to and below the slay, and such part being unclosed above and below, enables a projection or stud *e* to pass between the sides of said piece *d*. This projection *e* forms an abutment to the spring *h* which may be connected to the support *c*¹ if desired, and is shown guided in direction by the pin *h*¹ also connected to said support *c*¹. The block *d*¹ is shown capable of adjustment by release of the same between plate *d*² and set screw *d*⁴, and by subsequent operation of screws *d*³.

For the position shown in Figs. 1 and 3, 110

the spring h is assumed to be in compression, and is thus tending to force the slidable member d in a direction to release the reed, as indicated in Fig. 2. Under normal conditions this movement of release is prevented by the intervention of a locking piece k^1 attached to a cross bar k , which latter is capable of sliding in a direction at right angles with the movement of the part d , or thereabout. The piece k^1 when operated by the bar k is capable of sliding in and out of a gap or detent between the block d^1 and the slay or bracket thereon, as hereinafter described.

Referring more particularly to Fig. 4, it will be seen that the said bar is shown supported by rests, such as 1 , attached to a number of brackets beforementioned, one of which here shown being marked m , such brackets being connected to the slay front at suitable intervals along the length thereof. The extreme portion of said bar k is shown supported by a bracket n , the end of the bar being suitably shaped or provided so as to prevent its movement for unlocking purposes being excessive.

Referring to Fig. 6, o is the external portion of the ordinary shuttle box swell, touching which is a swinging lever p pivoted at p^1 , and capable on being moved on said pivot of moving a second lever q pivoted at q^1 . By this arrangement the movement of the lever q relatively to that of the swell o can be magnified. Also pivoted at q^1 is a lever arm r , which is arranged to be moved about its center of turn when the lever q is moved. This could be accomplished by making the shaft at q^1 revolvable and connecting both q and r thereto by an ordinary 40 shaft key. The said arm r has pivoted to it a finger r^1 , and when the shuttle enters the box o^1 the consequent movement of the swell o results in the finger r^1 being lifted clear of the shoe or deflector shown at s , and which 45 may be connected to the loom framing whether adjustable in position or not. Reference to Fig. 7 will show that this shoe is so shaped as to be capable of deflecting the finger r^1 , when the latter is not lifted clear 50 of said shoe, in a lateral direction, and thus causing the same to impinge against and move the bar k , with the result that the locking pieces, such as k^1 , are withdrawn from between the blocks d^1 of the parts d , and the 55 slay a or brackets m thereon, thus releasing the reed when the shuttle fails to enter the box or fails to operate the mechanism to lift the finger r^1 clear of the shoe s . The freedom of movement of the finger r^1 about 60 its center of turn near the end of the arm r , can be regulated by the degree of tightness of the nuts shown near said end.

A modification of the action of the parts in Fig. 6 is indicated in Fig. 5, in which 65 the shoe s is replaced by a bell crank lever

pivoted at s^1 , and one leg s^2 of which extends sufficiently as to come opposite the end of the bar k , while the other leg s^3 is capable of being situated in the path of the lever r^1 when the same is not lifted or when 70 the shuttle fails to enter the shuttle box. The leg s^2 is assumed to be at a lower level than that of the lever or finger r^1 , so that on the said finger moving forward for the reason given, the said leg is caused to operate the bar k as illustrated. By this means 75 it is not necessary that the finger r^1 should be capable of movement in two planes as in the other example.

It is obvious that the actions of the cross bar k and locking pieces k^1 are not confined to the precise method or arrangement illustrated, or that if pins on the pieces k^1 were arranged to enter holes in the blocks d^1 , or vice versa, the effect would be the same. 80 The lower edges of the member or clamp portion d are preferably hollowed out as indicated in Figs. 1 and 2, for the purpose of enabling the said member to fall away from the slay when released, as indicated 85 in Fig. 2, almost immediately the locking piece k^1 is withdrawn. A spring t is shown in Fig. 4 connecting the bracket n with the bar k , for the purpose of aiding the locking movement when the member d is pushed 90 back into position for becoming locked. For ordinary looms the members such as d , together with the remaining clamp parts c^1, c , may be pushed back into position after 95 stopping the loom.

We claim:—

1. In a loose reed motion for looms, a clamp for the reed comprising clamp connections which are constantly locked while the loom is working properly, but are movable transversely of the lower part of the loom slay, for release of the reed, should the shuttle stop in the shed, in combination with locking means for retaining the clamp connections in the said locked position, and means for automatically unlocking the same when the shuttle stops as aforesaid, substantially as herein set forth.

2. In a loose reed motion for looms, a clamp for the reed comprising clamp connections which are constantly locked while the loom is working properly, but are movable transversely of the lower part of the loom slay, for release of the reed, should the shuttle stop in the shed, in combination with locking members for retaining the clamp connections in said locked position, laterally and automatically movable means for unlocking said clamp connections when the shuttle stops as aforesaid, and means for so moving said locking members out of action, substantially as herein set forth.

3. In a loose reed motion for looms, a clamp for the reed comprising clamp connections which are movable transversely of 130

the lower part of the loom slay, for release of the reed, in combination with locking members for retaining said clamp connections in the locked position while the loom 5 is working properly, a connection to said locking members laterally and automatically movable for unlocking said clamp connections when the shuttle fails to enter the shuttle box, a pivoted finger piece adjacent to 10 said connection, movable in two planes, in the one plane for operating said locking member connection, and in the other during the normal working of the loom, and means for moving said finger piece in the two 15 planes aforesaid, substantially as herein set forth.

4. In a loose reed motion for looms, a clamp for the reed comprising hollowed out clamp connections which are movable transversely of the lower part of the loom slay, for release of the reed, locking members 20 capable of passing between the slay and

parts of the clamp connections, a cross bar to which said locking members are attached, and laterally and automatically movable for 25 unlocking said clamp connections, a pivoted finger piece adjacent to the end of said cross bar in connection with the swell of a shuttle box, for movement thereby, a pivoted lever upon which the said finger piece is pivotally 30 mounted for lateral movement, a deflector or shoe connected to a part of the loom, and for so laterally moving said finger piece, when the shuttle fails to enter the shuttle box, substantially as herein set forth. 35

In testimony whereof we have signed our names to this specification in the presence of two subscribing witnesses.
